UNITED STATES PATENT OFFICE.

DWIGHT S. RICHARDSON, OF BROOKLYN, NEW YORK.

DESIGN FOR A RANGE.

SPECIFICATION forming part of Design No. 16,518, dated February 9, 1886.

Application filed December 15, 1885. Serial No. 185,773. Term of patent 7 years.

To all whom it may concern:

Be it known that I, DWIGHT S. RICHARDSON, of Brooklyn, in the State of New York, have invented a Design for a Range, of which

5 the following is a specification.

The design of the shape and ornamentation of the range is shown in the accompanying drawing.

10 The doors of the range-front are flat upon the surface, with their edge portions rounding backwardly to the back edge, as shown at *a*, and the oven-doors are extended laterally at the hinge part *b*, to form two offsets or shoulders at *c*, and between these offsets the edge 15 of the door is rounding, and the top edges of the oven-doors are arched. The front plate, and in front of the beveled corners of the range, is flat, with beveled corners *e*, upon which there is a rustic Grecian pattern in 20 relief, cast as shown at *d* in the drawing. The base portion projects in front of the front plate, and the top plate of the range has a rounded edge at *g*.

In doors heretofore constructed for ranges

the surfaces have been ornamented with beads 25 or moldings, forming a panel. My door, being free from these lines and panels, has an appearance that is peculiar to itself.

I claim—

1. The design for a range, consisting of the 30 front plate, the projecting base, and the beveled corners, having the shape and ornamentation described and shown.

2. In a design for a range, the design of the 35 doors, consisting in the rounding edges from the back to the front, with the ornamentation, substantially as described and shown.

3. In a design for a range, the design of the 40 doors, consisting in the rounding edges from the back to the generally plain front, and the arched top, substantially as described and shown.

Signed by me this 10th day of December, A. D. 1885.

DWIGHT S. RICHARDSON.
